CONTROL VALVE MEANS

Elmer J. Dunham and Walter C. Yeakel, Battle Creek, Mich., assignors to Clark Equipment Company, Buchanan, Mich., a corporation of Michigan

Application September 12, 1936, Serial No. 100,515

4 Claims. (Cl. 121—46.5)

This invention relates to control valve means, and more particularly is directed to control valve means for effecting reciprocation of a hydraulically actuated piston.

5 The invention is particularly designed for the operation of a lift cylinder such as disclosed in the copending application of Elmer J. Dunham, Serial No. 94,926, filed August 8, 1936.

One of the primary objects of the present invention is to provide a compact valve structure for accomplishing reciprocation of a piston, which structure is of simplified design and can be readily formed from castings with only a small amount of machine work.

10 Another object of the present invention is to provide a valve structure which is capable of standardized production so that interchangeable valve members can be employed in the same valve housing without the necessity of individual lapping-in of the valve members.

A still further object of the invention is to provide a valve means of this type which can be easily controlled for movement into all of its various operating positions so that a minimum 15 of effort is required for shifting of the valve to effect reciprocation of the piston.

It is desirable, in a valve of this type, to utilize a construction so arranged and disposed that the valve member does not need to be positively restrained in any of its shifted positions, so that the continued application of shifting force may be eliminated. The present design produces a valve which is hydraulically balanced in each of its shifted positions so that it tends to stay in any 20 predetermined position until moved to another position by the shifting mechanism.

A further feature of the present invention resides in the provision of a valve structure which can be readily mounted directly on the cylinder enclosing the piston or load operating means and can be operatively connected directly to opposite ends of such a cylinder.

Other objects and advantages of the present invention will appear more fully from the following detailed description which, taken in conjunction with the accompanying drawing, will disclose to those skilled in the art the particular construction and operation of a preferred form of the present invention.

10 In the drawing:

Figure 1 is a sectional view through the valve taken substantially on line 1—1 of Figure 3;

Figure 2 is a sectional view taken substantially on the line 2—2 of Figure 3;

15 Figure 3 is an end elevational view of the valve

structures shown in detail in Figures 1 and 2; and

Figure 4 is a sectional view similar to Figure 2 showing the valve in one of its shifted positions.

While we have disclosed the present construction in its relationship to a cylinder of the type shown in the Dunham application above referred to, it is to be understood that the valve is capable of use in connection with other types of cylinders and for other purposes, and the invention is therefore not to be limited except as defined by the claims appended hereto.

Referring now in detail to the drawing, the valve body is indicated generally at 5 and comprises a substantially rectangular block having a plurality of openings 6 extending therethrough and adapted to receive securing means for mounting the valve body in position on extension 7 of a power cylinder indicated generally at 8, the power cylinder having the piston 9, of any design or preferred construction, guided for reciprocation therein.

The valve body 5 is provided with a longitudinal passageway 10, cylindrical in form, which is adapted to be machined within relatively close limits for receiving a reciprocating valve member 12 therein. One end of the passageway 10 is closed by the cap member 13 suitably secured to the end face of the body 5, while the opposite end is provided with a cap plate or packing gland member 14 secured to the opposite end face of the block and suitably recessed, as indicated at 15, to receive packing engaging the lateral surface of the valve stem 16. The packing is compressed into position about this surface by the packing gland nut 17 threaded into the recessed opening of the gland member 14.

The outer end of the valve stem 16 is provided with the projecting portion 18 fitting into a suitable socket formed in a clevis or attachment member 19 and secured thereto by the set screw 20. The member 19 is preferably provided with bifurcated arms 22 adapted to receive therebetween any suitable actuating means, such as a bell crank lever or the like, for producing reciprocation of the valve stem 16 to control the movement of the piston 9.

15 The valve body 5 is provided with an upwardly extending boss portion 25 suitably threaded to receive the supply conduit 26 for conducting fluid under pressure to the valve body 5. Immediately below the boss 25 there is formed in the valve body 5 the chamber 27 providing a manifold for supplying the three substantially annular 55

spaced inlet passageways 28, 29 and 30 communicating with the bore 18.

Projecting from one lateral surface of the valve body 8 there is provided a second offset portion 35 suitably threaded at one end to receive the exhaust conduit 36 connected to the inlet side of a fluid pump or the like and forming, with the valve body 8, the exhaust manifold 37 which is common to each of the exhaust passageways 38, 39 and 40, also communicating with the bore 18.

The side of the body 8 which is bolted to the top of the cylinder 8 is provided with a pair of spaced passageways or ports 42 and 43, communicating with the bore 18, the port 42 terminating in a cylindrical passage 44 disposed between the passageways 38 and 28, and the port 43 terminating in the passageway 45 spaced between the inlet passage 38 and the outlet passage 40.

The valve member 12 may be formed from a cylindrical piece of stock which is milled down in certain places to form portions of reduced diameter providing for entrance and exhaust of the fluid through the various ports and manifold passageways. These portions are indicated respectively at 50, 52, 53, 54 and 55. At opposite ends of the valve member there are provided annular flanged portions 60 and 62, each of which is provided with a small opening 63 extending therethrough and providing a bypass for exhausting the fluid from between the flanges 60 and 62 and the closure plates 13 and 14 as the valve is reciprocated into its various positions. In the central portion of the valve member there is provided a pair of annular flange members 65 and 66 spaced apart a distance as indicated by the axial length of the portion 53 of the valve member. The valve is also provided with enlarged cylindrical portions 67 and 68 interposed, respectively, between the flanges 60 and 65 and 62 and 66. The valve is guided for reciprocation in the bore 18 by the engagement of these enlarged surfaces 68, 62, 65, 66, 67 and 68 with the defining wall of the bore.

The valve member is shown in its neutral position in Figures 1 and 2. In this position, the supply passageway 28 communicates directly with the exhaust passageway 38 about the reduced portion 53 of the valve member, while the passageways 44 and 45 are closed off from both the supply manifold 27 and the exhaust manifold 37, by reason of the cylindrical portions 67 and 68. With the piston as shown in Figure 2, no pressure is being applied to either side of the piston, since the inlet conduit is in direct communication with the outlet conduit 36. Upon moving the valve stem 16 to the right until the flange 62 moves up against the inner surface of the closure cap 14, the portion 68 of the valve member is moved into a position closing the passageway 40, as shown in Figure 4. At the same time, the supply passageway 38 is placed in communication with the passageway 45 about the reduced portion 54 of the valve member providing for direct flow of fluid under pressure from the manifold 27 through passageways 38 and 45 to the port 43. From the port 43 the fluid passes through the passageway 70 into the right hand end of the cylinder 8 and consequently tends to move the piston 8 to the left.

At the same time, the portions 66 and 65 of the member 12 move into position on opposite sides of the passageway 28 so that this passageway delivers fluid against opposite faces of the members 65 and 66 to hold the valve in balanced position. The portion 67 likewise moves into po-

sition to close passageway 28 and opens the path between passageways 44 and 38 about the reduced portion 50 of the valve member. As a result, fluid on the left hand side of the piston 8 is exhausted through the passageway 38 to the exhaust manifold 37, allowing the piston to move to the left under the influence of the fluid pressure entering through the port 43.

With the piston in position at the left hand end of cylinder 8, the valve member 12 is moved from the position shown in Figures 1 and 2 to the left to bring the flange 60 toward the closure plate 13. This moves the portion 67 of the valve into position to close off passageway 38 and to open the path between passageways 28 and 44 about the reduced portion 52 of the valve. As a result, fluid under pressure passes about the reduced portion 52 of the valve to the port 42 and thence through the passageway 72 to the left hand side of the piston 8. At the same time, the members 65 and 66 move into position on opposite sides of the passageway 38 to effectively close off this passageway, and also to close off communication between passageway 28 and passageway 38.

The portion 68 of the valve moves into position closing the inlet passageway 38 to provide for balanced pressure against adjacent faces of the portions 66 and 68 to hold the valve in shifted position. This movement of the portion 68 opens communication between passageways 45 and 40 about the reduced portion 55 of the valve, thus placing the right hand portion of cylinder 8 in communication through port 43 with the exhaust manifold 37. As a result, the piston 8 moves to the right into the position shown in Figure 2.

It is therefore apparent that upon shifting of the valve in either position, the respective inlet and outlet ports will be placed in communication with opposite ends of the cylinder to effect proper reciprocation of the piston, and that the central passageway 28 of the supply conduit will conduct fluid under pressure against equal and opposite faces of the valve member to hold the valve in balanced position so that there is no tendency of the valve to move out of either of its shifted positions.

Further, when the valve is in the neutral position shown in Figure 2, the fluid pressure from the passageways 28 and 38 exerts equal pressure on opposite faces of the flange 66, thereby holding the valve stabilized in this position. This is of distinct advantage in that it relieves the shifting mechanism of stresses incident to holding the valve in either of its shifted positions against fluid pressure while the end construction of the valve members, including the flanges 60 and 62, serves as a cushioning means preventing the valve from being moved too abruptly into either of its limited positions.

Due to the fact that the passageway 10 and the external annular surface of the member 12 can both be machined within relatively close limits, and fluid pressure is acting axially along the contact surfaces therebetween, the valve member 12 is cushioned for sliding movement, and further, interchangeable valve members may be employed in the same valve body without requiring any lapping-in of the valve members to provide a close fit.

Since the valve body is of a simplified construction and requires only the machining of the axial bore 18 and the tapping of the openings for the closure plates, securing means, and the inlet and

exhaust conduits, a valve of simplified and economical construction is produced.

We are aware that various changes and modifications can be made with respect to the dimensions and proportions of various of the parts shown herein, and that the valve is equally useful for purposes other than that described specifically herein as an illustrative embodiment of the invention. We therefore do not intend to be limited, except as defined by the scope and spirit of the appended claims.

We claim:

1. A valve comprising a valve body formed as a rectangular block having a longitudinal bore therethrough, a boss on one side of said block defining an intake manifold having means for receiving an intake conduit and having a plurality of axially spaced annular passageways extending about and communicating with said bore, a second boss on an adjacent side of said block defining an exhaust manifold having means for receiving an exhaust conduit and having a corresponding plurality of axially spaced annular passageways, two of said intake passageways being disposed intermediate two adjacent exhaust passageways, ports communicating with said bore between certain of said intake and exhaust passageways and opening out on the next adjacent face of said block, and means disposed for axial shifting movement in said bore to place said ports in selective communication with said intake and outlet passageways, one of said intermediate intake passageways serving only to permit balanced pressure being exerted on said shifting means in said selected shifted positions.

2. A valve comprising a valve body having a longitudinal bore therethrough, an exhaust manifold in one side of said body having three annular exhaust passageways in communication with said bore, an intake manifold in said body having three annular passageways in communication with said bore, a valve plunger in said bore having reduced portions separated by annular enlargements closing said bore axially, separate ports in said valve body having annular portions communicating with said bore intermediate

diate an intake and an exhaust passageway disposed adjacent each end of said bore, said plunger being shiftable from a normal position with certain of said enlargements closing said ports into a position to place one of said ports in communication with an intake passageway and the other of said ports with an exhaust passageway, the third intake and exhaust passageways being thereby separated by another of said enlargements.

3. A valve comprising a valve body having a longitudinal bore therethrough, an intake manifold and an exhaust manifold in said body, each having three annular passageways in communication with said bore, one exhaust passageway being disposed adjacent each end of said bore and having a corresponding intake passageway spaced axially inwardly thereof, ports in said body opening into said bore intermediate said pairs of intake and exhaust passageways, the other exhaust passageway being disposed between one of said corresponding intake passageways and the remaining intake passageway, a valve plunger mounted for reciprocatory movement in said bore and having reduced portions spaced apart by annular enlargements axially closing said bore, said plunger in normal position having said enlargements disposed to provide communication between said other exhaust passageway and said remaining intake passageway, and shiftable in either direction to provide simultaneous communication between one of said ports and an associated intake passageway and the other of said ports and an associated exhaust passageway and to shut off communication between said remaining intake and the other exhaust passageway.

4. The combination of claim 3 characterized in that said plunger has enlargements whereby in either shifted position said remaining intake passageway is capable of transmitting fluid under pressure to opposite faces of said enlargements, whereby said plunger is maintained balanced in either of its shifted positions.

ELMER J. DUNHAM. 45
